The ornamental design for a head of lawn brush, as shown and described.

DESCRIPTION

FIG. 1 is a perspective view of a head of lawn brush showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, showing the status while in use.

The broken lines illustrate portions of the head of lawn brush that form no part of the claimed design. The broken lines showing a handle in FIG. 8 are for the purpose of illustrating environmental structure, and form no part of the claimed design.
